Primary Examiner — Rebecca Tsehay(74) *Attorney, Agent, or Firm* — Jacob Raul Compton; Johnny Chwang(57) **CLAIM**

The ornamental design for a cocktail smoker, as shown and described.

DESCRIPTION

FIG. 1 is a front-top perspective view of a cocktail smoker showing my new design;

FIG. 2 is a front-bottom perspective view thereof;

FIG. 3 is a front elevation view thereof, where the rear elevation view is mirrored thereto;

FIG. 4 is a left elevation view thereof, where the right elevation view is mirrored thereto;

FIG. 5 is a top plan view thereof; and,

FIG. 6 is a bottom plan view thereof.

The broken lines in the drawings illustrate portions of the cocktail smoker which form no part of the claimed design.
